Attorney.

UNITED STATES PATENT OFFICE.

ARAM SHENHAN, OF PROVIDENCE, RHODE ISLAND.

FINGER GUARD FOR SMOKING PIPES.

Application filed March 7, 1923. Serial No. 623,365.

To all whom it may concern:

Be it known that I, ARAM SHENHAN, a citizen of the United States, residing at Providence, in the county of Providence and State of Rhode Island, have invented certain new and useful Improvements in Finger Guards for Smoking Pipes, of which the following is a specification.

My invention relates to a device for tamping a charge of tobacco in a pipe bowl, and has for its essential objects evenness of pressure on the charge, protection of the finger from heat during the tamping operation, facility of attachment and detachment of the device from the pipe bowl, facility of operation, and inexpensiveness of construction.

To the above ends essentially my invention consists in such parts and in such combinations of parts as fall within the scope of the appended claims.

In the accompanying drawings which form a part of this specification,

Figures 1 and 2 are a side and front elevation respectively of my novel guard,

Figure 3, a section on line 3—3 of Figure 1, and

Figure 4, a section of the guard on line 4—4 of Figure 2, and of a pipe upon which the guard is mounted.

Like reference characters indicate like parts throughout the views.

My device consists in detail of a base 6 having at its rear end a depending flat finger 7, and at the other end spaced depending fingers 8. The three described fingers are resilient and the parts 6, 7, and 8 constitute a clamping member for detachable mounting on a pipe bowl. The flat portion 6 is adapted for resting on the edge of the bowl; the finger 7, against the exterior of the bowl, and the fingers 8, against the interior of the latter. Near its top the finger 7 has rearwardly directed integral lateral lugs 9. Hence the parts thus far described may be cut and bent up from a blank of thin metal.

An operating member consists of an arm comprising a horizontal rearwardly directed lower portion 12, a vertical intermediate portion 13, and a forwardly directed upper portion 14, fast to or integral with whose free extremity is a vertical disk 15. Integral with the portion 12 are upright lateral ears 17. The parts 12, 13, 14, 15 and 17 may,

therefore, be cut and bent from a single flat metallic blank.

The lugs 9 and ears 17 have respectively perforations 19 and 20 to receive a pintle or pivot member 22, around which is coiled a helical spring 24 having one arm 25 resting against the finger 7, and another arm 26 abutting against the arm portion 12. The end of the latter portion is normally held by the spring against the outer face 60 of the finger 7 which forms a stop for the arm in its rearward travel.

The operation of my guard may be observed in Figure 4 wherein is shown the bowl 28 and a fragment 29 of the stem 70 of a pipe. The fingers 7 and 8 embrace the wall of the bowl, and in full lines, the operating arm is in normal upright position. When it is desired to tamp a charge 75 of tobacco in the bowl the operator's finger is pressed against the arm to force the disk 15 the necessary distance into the bowl. After which pressure is released and the arm returns to elevated position through the action of the spring. 80

It will be understood that because of the resiliency of the depending fingers the operator may slide my device into engagement with the bowl or disengage the same from the latter at will, so that the user 85 may employ the device only while smoking. It will be further noted that the operator's finger is protected from heat while depressing the charge in the bowl; and that the structure comprises a minimum of parts in 90 inexpensively assembled.

I claim:

1. In a guard for a smoking pipe, a clamping member comprising a base, and resilient fingers depending from the base, lateral lugs on one of the fingers, an operating arm comprising an intermediate portion, a horizontally disposed lower portion, an upper portion disposed in the direction of the lower portion, a disk on the upper 100 portion, ears on the lower portion, and a pintle mounted in the lugs and ears. 95

2. In a guard for a smoking pipe, a clamping member comprising a base, resilient clamping fingers depending from the base, lateral lugs on one of the fingers, an operating arm comprising an intermediate portion, a forwardly directed lower portion adapted to abut against the lug carrying finger, a forwardly directed upper portion, 110

a disk on the upper portion, lateral ears on the lower portion, a pintle in the lugs and ears, and a spring on the pintle engaging the lower portion of the arm and said finger for pressing said lower portion of the arm against said finger.

3. In a guard for a smoking pipe, a clamping member engageable with a bowl, an operating arm pivotally mounted on the

member and engageable at its inner end with the member, a disk on the outer end of the arm, and resilient means engaging the arm and member for pressing the inner end of the arm into engagement with the member.

In testimony whereof I have affixed my ¹⁵ signature.

ARAM SHENHAN
